CLAIM

The ornamental design of a lantern, as shown and described.

DESCRIPTION

FIG. 1 is a top front right perspective view showing our new design for a lantern.

FIG. 2 is a front view thereof.

FIG. 3 is a right side view thereof.

FIG. 4 is a back view thereof.

FIG. 5 is a left side view thereof; and,

FIG. 6 is a top view thereof.

The broken lines in the drawings depict portions of the lantern that form no part of the claimed design.
